UNITED STATES PATENT OFFICE.

HOWARD E. BARLOW, OF PROVIDENCE, RHODE ISLAND.

MACHINE FOR MAKING TOOTHPICKS.

SPECIFICATION forming part of Letters Patent No. 592,074, dated October 19, 1897.

Application filed March 1, 1897. Serial No. 625,462. (No model.)

To all whom it may concern:

Be it known that I, HOWARD E. BARLOW, of Providence, in the county of Providence and State of Rhode Island, have invented certain new and useful Improvements in Machines for Making Toothpicks; and I do hereby declare that the following is a full, clear, and exact description thereof, reference being had to the accompanying drawings, and to the letters of reference marked thereon, which form a part of this specification.

This invention relates to the class of wood-working machinery, and its object is to produce a machine for making toothpicks and other like small articles of wood, properly shaped, pointed, and finished ready for use as they come from the machine.

It is fully explained and illustrated in this specification and the accompanying drawings.

Figure 1 represents a top view of the machine. Fig. 2 is a side elevation with the upper half of the machine shown in section. Fig. 3 is a vertical cross-section taken on line $x x$ in Fig. 1. Fig. 4 is a perspective view of one of the knives. Fig. 5 is a vertical cross-section of the end of one of the rolls, showing how the knives are held in place. Fig. 6 is a perspective view of one of the blocks and a finished toothpick.

The construction of the machine is as follows: Two vertical side frames A A are bolted fast to the bed-plate C.

D D are two standards, which are also fastened to the bed-plate C, and connected together at the top by the bar N. A driving-shaft a is held in bearings attached to the side frames A and standards D, and has a driving-pulley F on its outer end. A like shaft a' is also held in like bearings in the side frames and the standards, and is connected with shaft a' by two gear-wheels b b'. These two shafts a a' carry the cutter-rolls d d, and are divided into two parts each at f, and the parts are connected together at that point by means of loose couplings c', that will allow the rolls d d to approach each other or to recede without disturbing the parts of the shafts held in the bearings attached to the standards D D. Another shaft J, having bearings in the outer side frame A and the inner standard D, is placed below to operate

the feed motion at the outer side of the machine. A short vertical shaft k is held between the upper part of the standards D in 55 bearings fast on arms v v, projecting from the inner standard D, and a worm-gear S, fast on the upper end of the shaft k engages in a worm g, fast on the shaft a, and a bevel-gear n on the lower end of the shaft k, engages 60 with a bevel-gear n', fast on the end of the shaft J, which gives motion to the feed. Two plates L L' are held to slide horizontally in ways on the side frames A. To give motion to these plates, a segment-gear h is placed 65 under each plate on short shafts having bearing attached to the side frame A, and engage in toothed racks a'' a'', secured to the under side of each plate L L'.

A gear-wheel r, fast on the outer end of the 70 shaft J, engages with a gear-wheel r', held on a stud in the side frame. Each gear-wheel r has a crank o, fast on its outer face, and these cranks are connected by rods j j' with cranks c'' c''' on the ends of the segment-shafts, so 75 that as the gear-wheels r r' revolve they will give motion to the segments and through the racks a'' a'' to the tables L L'. The boxes i i', that hold the shaft of the rolls d d, are held to slide vertically a short distance between 80 two posts H H, to allow the rolls to approach or recede from each other, which is accomplished by means of the following mechanism: Two short horizontal shafts l l are held in bearings on the posts H, and each of these 85 shafts has a crank s on one end, and these two cranks are connected by a rod y with a crank m on the upper end of the shaft k. Cross-arms e' are made fast on each of the shafts l l. These arms are connected on the 90 one side by a bar and straps S'' to each lower box i, and the arms on the other side are connected with the upper boxes at S', so that when the shafts l l are rocked by the crank m and connecting-bar y the arms e' on one 95 side will rise and draw up the lower boxes and at the same time the arms on the other side of the shaft will move down and push down the upper boxes. In this way the rolls will be made to approach each other to cut 100 the points of the toothpicks, and when the shafts l l are rocked the other way by the crank m the rolls will be separated.

The construction of the rolls d and arrange-

ments of the knives v' on them to enable them to cut the picks to a fine point and support them while it is being done is this: The knives v' are made with sharp notches (see Fig. 4)

5 of the shape desired for one side of the picks and set radially in the rolls, so that only the teeth of the knives project, and the mode of holding them in the roll is shown in Fig. 5, in which d is the roll, v' the knives, which

10 are beveled away at the outer corners h of their ends, and a collar z , having a concave inner face, is fitted to screw on the shaft of the roll and project over the incline on the ends of the knives and hold them in place.

15 Between each of the knives a groove z' is made deep enough to receive that part of the knife that projects above the surface of the roll, and the two rolls are so geared together as to bring the knives of one roll in the 20 grooves of the other roll. This enables the rolls to come close together and cut the picks to a fine point, as the roll d on each side of a groove z' affords the necessary support to the small part of the wood that constitutes the 25 point of the toothpicks.

In operation the blocks of wood R , (see Fig. 6,) in which shape they are provided for the purpose, are placed before table L (see Fig. 2) when it is clear out to the left, and as the 30 shaft J revolves the cranks on the gears $r r'$, and by means of rods j , the segment-gears move the plates $L L$ toward each other and push the blocks $i i$ in between the rolls $d d$,

35 which are made to revolve very fast, the knives v' will cut the upper and lower surface of the block in flutes, the grooves between these flutes meeting in the middle and making the block into separate picks. As the wood passes between the rolls it is met by 40 the open jaws E on the plate L' , which, as that plate is moved back, are closed by an incline plate m' , fast on the frame, that presses down the arm e'' and causes the jaws to grip tight on the block and draw it through the 45 rolls as the plate goes back. At the same time the crank m will draw on the rod y and cause the shafts $l l$ to draw the rolls together and cut the picks to a point, tapering down from one-third or so from the other end. As 50 the crank $r r'$ completes a revolution the plate L is again moved away from the rolls and is ready to receive another block. As the plate L approaches its outer limit the arm e''' passes up the incline n'' , and the jaws open and discharge the picks.

Having thus described my improvements, I claim as my invention—

1. In a machine for making toothpicks the combination of two rolls having notched 60 knives on their peripheries longitudinal grooves made in the rolls between said knives, and arranged to run together with the knives in one roll entering the grooves in the other roll, substantially as described.

65 2. In a machine for making toothpicks the

combination of two rolls having notched knives on their peripheries longitudinal grooves made in the rolls between said knives, and arranged to run together with the knives in one roll entering the grooves in the other 70 roll, with means for feeding the blocks of material to said rolls, substantially as described.

3. In a machine for making toothpicks the combination of two rolls having notched 75 knives on their peripheries, grooves made in the rolls between each two knives, and arranged to run together with the knives in one roll entering the grooves in the other roll, with means for causing the rolls by the operation of the machine, to alternately approach, and to recede from each other, substantially as described.

4. In a machine for making toothpicks the combination of two rolls having notched 85 knives on their peripheries grooves made in the rolls between each two knives, and arranged to run together with the knives in one roll entering the grooves in the other roll, a reciprocating feed-motion consisting of two 90 plates sliding in ways, with means for causing the two plates by the operation of the machine to move forward and back, substantially as described.

5. In a machine for making toothpicks the 95 combination of two rolls having notched knives on their peripheries grooves made in the rolls between each two knives, and arranged to run together with the knives in one roll entering the grooves in the other roll, 100 boxes or bearings for said rolls held to slide in ways toward, or from each other, rocker-shafts held in bearings over said boxes, cross-arms fast on said rocker-shafts, connections from said arms on one side of each shaft to 105 the lower boxes, and connections from the arms on the other side of each shaft to the upper boxes, with means for operating said rocker-shafts, substantially as described.

6. In a machine for making toothpicks the 110 following instrumentalities: two rolls having knives set in their peripheries, and having grooves in them between the knives, sliding boxes for said rolls to turn in, rocker-shafts placed over said boxes with arms connected to the boxes, sliding tables to carry the wooden blocks, racks on said tables with segment-gears engaging in said racks, a feed-shaft with gears and cranks to move said segment-gears, a worm-gear engaging with a 115 worm on a driving-shaft, and a connection between the worm-gear and said rocker-shafts, substantially as described.

In testimony whereof I have hereunto set my hand this 26th day of February, A. D. 125 1897.

HOWARD E. BARLOW.
In presence of—
BENJ. ARNOLD,
M. E. LAWTON.
